UNITED STATES PATENT OFFICE.

WILLIAM A. CHRYST, OF DAYTON, OHIO, ASSIGNED TO THE DAYTON ENGINEERING LABORATORIES COMPANY, OF DAYTON, OHIO, A CORPORATION OF OHIO.

IGNITION APPARATUS.

Application filed December 17, 1920. Serial No. 431,434.

To all whom it may concern:

Be it known that I, WILLIAM A. CHRYST, a citizen of the United States of America, residing at Dayton, county of Montgomery, State of Ohio, have invented certain new and useful Improvements in Ignition Apparatus, of which the following is a full, clear, and exact description.

This invention relates to ignition timer apparatus for use in connection with internal combustion engines.

Among the objects of the invention is the provision of novel arrangement of speed responsive mechanisms and manually operated mechanisms for controlling ignition timing apparatus whereby to reduce the cost of manufacture and to place the manually operated timing lever or other member in a convenient position.

Other and further objects of this invention will be apparent from the following description, reference being had to the accompanying drawings, wherein a preferred embodiment of the present invention is clearly shown.

In the drawings Fig. 1 is a plan view of the ignition unit embodying the present invention;

Fig. 2 is a longitudinal sectional view of Fig. 1 taken substantially on the line 2-2 of Fig. 1;

Fig. 3 is a plan view of the timer, the distributor having been removed; and

Fig. 4 is a sectional view taken on the line 4-4 of Fig. 2.

Referring to the drawings, timer housing 20 is constructed to provide a chamber 21 for containing the timer controlling elements to be described and for supporting timer base plate 22 in which a bearing 23 is provided. The housing 20 is constructed also to provide a reduced end portion 24 by means of which the housing may be conveniently mounted upon an engine frame. The lower end of the portion 24 of the housing is provided with a bearing 25. The bearing 25 supports the upper end of a cam shaft 26 within a hollow, engine driven shaft 27. The lower end of shaft 27 is supported by the lower end of bearing 25 and carries an engine driven gear 28. The upper end of shaft 27 supports a plate 30 (see Fig. 4) upon which are mounted a plurality of weight members 31 each provided with a recess 32 cooperating with a

finger 33 formed preferably integrally with a sleeve 34 which is journaled upon an intermediate portion of the shaft 26. The weight members 31 are normally maintained in the position shown in Fig. 4 by means of springs 35 each connected at one end with a weight member 31 by means of a stud 36 and at the other end with the plate 30 by means of a stud 37.

The cam shaft 26 is provided with a straight slot 40 and the sleeve 34 is provided with spiral or oblique slots, one of which is shown at 41. A pin 42 passes through slots 40 and 41 and its ends are supported by a grooved collar 43 slidably mounted upon the sleeve 34. Pins 44, which cooperate with collar 43, are supported by lever arms 45 which are screwed upon a shaft 46. A manual advance lever 47 is mounted upon the end of shaft 46 which projects beyond the housing 20.

The upper end of shaft 26 supports a timer cam 50 and a distributor rotor 60. Cam 50 cooperates with a plurality of circuit interrupters each including a breaker lever 51 and a pair of timer contacts 52, 53. These contacts are arranged in the usual manner to control the passage of current to an ignition coil. The rotor 60 cooperates with a distributor head 61 in the usual well known manner to distribute to the various stationary distributor terminals 62 which are arranged to be connected with the various spark plugs of an engine.

When the shaft 27 is rotated by an engine through the gear 28 the weights 31 will fly out more or less according to the speed to control the angular relation between the sleeve and intermediate member 34 and the shaft 27. In this manner the angular relation between the cam shaft 26 and the shaft 27 is controlled since sleeve 34 and shaft 26 are connected by the pin 42. The ignition timing is controlled manually by operating the lever 47 which causes the pin 42 to be shifted up and down thereby camming the shaft 26 and the sleeve 34 relatively to each other to vary the angular relation between these members.

It will be apparent from the foregoing description accompanied by the drawings that the control of the timer cam has been effected by means of very simple mechanism and that the construction and arrangement of the parts of this mechanism are con-

due to reduction of cost of manufacture. The arrangement of the manually operable control mechanism above the speed responsive mechanism is such as to bring the manual advance lever 47 up near the distributor head. In many installations on automobile engines it is found desirable to have the timer lever located in this manner in order to facilitate attachment to the control mechanism of the steering column.

While the form of mechanism herein shown and described constitutes a preferred form of embodiment of the invention, it is to be understood that other forms might be adopted, all coming within the scope of the claims which follow.

What I claim is as follows:

1. In an ignition timer, the combination with a circuit interrupter, a cam for operating the interrupter, and speed controlled means for advancing the cam; of manually controlled means for varying the relative angular position of the cam to the speed controlled means.

2. In an ignition timer, the combination with a circuit interrupter, a cam for operating the interrupter; and speed controlled means for advancing the cam; of manually controlled means located between the cam and said means for varying the relative angular position of the cam to the speed controlled means.

3. In an ignition timer, the combination with a circuit interrupter; of a cam for operating the interrupter; and means for driving the cam including an engine driven shaft, a cam shaft, an intermediate member, speed responsive means connecting the engine driven shaft and the intermediate member for controlling the angular relation of said engine driven shaft and said member, and manually controlled means for connect-

ing the intermediate member with the cam shaft and for controlling the angular relation between said member and cam shaft.

4. In an ignition timer, the combination with a circuit interrupter; of a cam for operating the interrupter; and means for driving the cam including an engine driven shaft, a cam shaft supported by the engine driven shaft, an intermediate member supported by the cam shaft, speed responsive means connecting the engine driven shaft and the intermediate member for controlling the angular relation of said engine driven shaft and said member, and manually controlled means for connecting the intermediate member with the cam shaft and for controlling the angular relation between said member and cam shaft.

5. In an ignition timer, the combination with a circuit interrupter; of a cam for operating the interrupter; and means for driving the cam including a hollow, engine driven shaft, a cam shaft having a bearing within said engine driven shaft, bearings supporting respectively, one end of the engine driven shaft and one end of the cam shaft, a sleeve supported by said cam shaft intermediate said bearings, speed responsive means connecting the engine driven shaft and the sleeve for controlling the angular relation of said engine driven shaft and said sleeve, and manually controlled means for connecting the sleeve and cam shaft and for controlling the angular relation between said sleeve and cam shaft.

In testimony whereof I hereto affix my signature.

WILLIAM A. CHRYST.
